UNITED STATES PATENT OFFICE.

THOMAS J. HAYES, OF BOSTON, MASSACHUSETTS.

BELT-CUTTING TOOL.

1,231,021.

Specification of Letters Patent. Patented June 26, 1917.

Original application filed October 23, 1915, Serial No. 57,456. Divided and this application filed April 5, 1917. Serial No. 159,911.

To all whom it may concern:

Be it known that I, THOMAS J. HAYES, a citizen of the United States, residing at Boston, in the county of Suffolk and State of Massachusetts, have invented new and useful Improvements in Belt-Cutting Tools, of which the following is a specification.

This invention relates to tools for cutting off the ends of round leather belting to form 10 square ends adapted to be abutted together, for punching the belting near said ends to form holes for the reception of the legs of a staple-shaped wire-coupling, and for clenching the legs of the coupling upon adjacent 15 ends of the belting. A tool of this character in common use comprises a pair of body members having opposed faces between which the belting is grasped, and crossed levers fulcrumed together between the said 20 members, and so connected with the members that the faces thereof are moved toward and from each other by the levers and are maintained in parallelism with each other, one of the members being provided with a perforating 25 punch and with a cutter projecting inwardly from the member and coöperating with a shearing edge at one end of a belt-receiving recess in the other member in cutting off the end of a length of belting inter- 30 posed between the members, the members being provided with extensions formed to co-operate in clenching the belt coupling.

My Patent, 1,179,830, dated April 18, 1916, discloses certain improvements relating to 35 the cutting and punching devices of a tool of the character above mentioned. In another application filed by me October 9, 1916, Serial No. 124,465, of which this application is a division, I have shown certain improvements 40 relating to the punching devices, and other improvements relating to the cutting devices. The last-mentioned improvements hereinafter described and claimed, form the subject-matter of this application.

45 Of the accompanying drawings forming a part of this specification,—

Figure 1 is a side elevation of a tool embodying my invention, the body members being open.

50 Fig. 2 is a similar elevation, the body members being closed.

Fig. 3 is a section on line 3—3 of Fig. 2.

Fig. 4 is a fragmentary perspective view showing a portion of one of the members.

55 Fig. 5 is a section on line 5—5 of Fig. 2.

The same reference characters indicate the same parts in all of the figures.

In the drawings,—12 and 13 represent the body members of a belt-cutting and punching tool, said members being termed for convenience of description the lower and upper member, respectively, although it is obvious that the tool may be used with either member uppermost. 14 and 15 represent crossed levers fulcrumed together at 16 between the 60 body members, each lever having a longer and a shorter arm. The shorter arms of the levers are connected with the members by pivot-studs 17, located in sockets in the members formed to closely fit the studs. The 65 longer arms of the levers are engaged with the members by studs 18, located in longitudinal slots 19 in the members, the arrangement being such that when the levers are moved from the position shown by Fig. 1 70 to that shown by Fig. 2, the members are closed and are constantly maintained parallel with each other. The members are provided with coupling-clenching extensions 75 12^a and 13^a adjacent to the punch.

The construction thus far described is well known and is not claimed by me, this embodiment of my invention relating to the improvements next described in the cutting means.

80 The member 13 is provided with a belt-receiving recess 21 opening toward the inner end of the member, a flat recessed side 22 intersecting the wall of said recess to form a shearing edge, and opposed parallel knife-guiding shoulders 23 projecting from said recessed face.

85 24 represents an elongated knife rigidly attached at one end to the member 12 by screws 25 and extending from the member 95 12 onto the recessed face 22 of the member 13. The knife has a cutting edge 26 preferably curved, as shown by Figs. 1 and 2, and adapted to coöperate with the above-described shearing edge on the member 13. 100 The flat inner side of the knife is in sliding contact with the recessed face 22, and the parallel longitudinal edges of the knife are in sliding contact with the shoulders 23. The flat outer side of the knife is in sliding 105 contact with one of the shorter arms of the lever 15, as best shown by Fig. 5.

When the members are closing, the knife is confined and guided at both its sides by the face 22 and the lever arm 15, so that its 110

cutting edge cannot deviate from an exact predetermined path, and therefore cannot contact injuriously with the shearing edge on the member 13. The opposite longitudinal edges of the knife are at the same time maintained in sliding contact with the shoulders 23 so that edgewise displacement of the portion of the knife that projects over the member 13 is impossible. It will be seen, 10 therefore, that the described construction provides cutting means of a very simple and durable character.

When the members are opened the screws 25 are exposed, so that the knife can be 15 readily attached and detached, the knife being slideable longitudinally between the recessed face 22 and the lever arm 15. To facilitate the insertion of the knife and prevent liability of the operator's fingers being 20 cut by the cutting edge while inserting the knife, I provide the latter with an orifice 28 adapted to receive a pin whereby pressure may be exerted to move the knife to place.

It will be seen that the face 22 and shoulders 23 constitute a three-faced knife guide, one face of which intersects the wall of the belt-receiving recess 21 to form a shearing edge, and that the shorter arm of the lever 15 constitutes a fourth side of the knife 30 guide, so that the portion of the knife between its inner end and cutting edge is entirely surrounded by guide members in sliding contact with its sides and longitudinal edges.

35 The sliding engagement of the outer end portion of the knife with the face 22 and shoulders 23 of the member 13, and with the lever 15, and the rigid attachment of the inner end portion of the knife with the 40 member 12, maintain the members in exact alignment with each other and prevent either member from being deflected laterally from its path of movement.

I desire to call especial attention to the 45 fact that the shoulder 23, which is the upper shoulder as shown in the drawings, is spaced from the inner end of the recess 21, so that the face 22 has an extension 22^a crossing the inner end of the recess, as shown in 50 Fig. 4. A portion of the inner side of the knife bears on the extension 22^a and overlaps the inner end of the recess when the knife is moving forward, so that the cutting edge can not by any possibility be deflected to 55 contact injuriously with the shearing edge of the member 13.

I claim:

1. A tool of the character stated, comprising

ing an upper and a lower body member, the upper member having a belt-receiving recess opening toward the inner end of the member, and a flat recessed side face intersecting the wall of said recess to form a shearing edge, said member being provided with opposed parallel knife-guiding shoulders projecting from said recessed face, a knife rigidly attached at one end to the lower member and having parallel longitudinal edges in sliding contact with said shoulders, a cutting edge at one end, and flat inner and outer sides, the inner side being in sliding contact with said recessed face and the cutting edge being adapted to coöperate with said shearing edge, and operating means maintaining the members 60 parallel, said means including a lever in sliding contact with the outer side of the knife, and confining the latter against the said recessed side face.

2. A tool of the character stated, comprising a pair of body members, one having a three-faced knife guide and a belt-receiving recess, a portion of which intersects one face of said guide to form a shearing edge, an elongated knife rigidly attached to the other 85 member and projecting therefrom to co-operate with said shearing edge, the inner side and longitudinal edges of said knife being in sliding contact with the three faces of said guide, and operating means maintaining the members parallel and including a part bearing on the outer side of the knife 90 and forming the fourth face of a guide which entirely surrounds a portion of the knife.

3. A tool of the character stated, comprising a pair of body members, one having a belt-receiving recess and a recessed face extended across the inner end of said recess and intersecting a wall of the same to form 100 a shearing edge, said member having also a knife-guiding shoulder extending lengthwise of said face and spaced from the inner end of the recess, a knife rigidly attached to the other member, and operating means 105 maintaining the members parallel, means being provided for confining the knife in sliding contact with said face and shoulder, so that the inner side of the knife overlaps the inner end of the recess, and is prevented 110 from contacting injuriously with said shearing edge.

In testimony whereof I have affixed my signature.

THOMAS J. HAYES.
